CROSS-WOUND WARP BEAM

Gustav Kahlisch, Gladbach-Rheydt, Germany,
assignor to W. Schlafhorst & Co., Gladbach-Rheydt, Germany, a corporation of Germany

Original application July 11, 1933, Serial No. 679,957. Divided and this application October 4, 1935, Serial No. 43,615. In Germany August 17, 1932

2 Claims. (Cl. 28—37)

The wet treatment of yarn, that is bleaching, dyeing and the like, on a perforated beam is generally known in itself. However, by employing beams of the ordinary winding-formation, the 5 dyeing-through is irregular, because it is difficult to carry out an evenly loose formation of the yarn-body. It has therefore been attempted to wind the warp beams in a self-supporting cross-wound cheese shape in order thereby to obtain 10 a porous yarn body. But such warp beams of the customary cross-wind show again the drawback that the two sides of the yarn-body taper off owing to the pronounced crossing of the threads. As a consequence, the outermost threads 15 coming to rest on a constantly decreasing diameter, become shorter and shorter, and break when running off the beam in consequence of the increasing tension.

The present invention has for its object to do 20 away with this drawback of self-supporting cross-wound warp beams by carrying out the winding-on at the sides of the yarn-body more densely, so that the yarn-body is cylindrical up to the ends, or only very slightly tapered at the 25 sides, so as to show no drawbacks in practice. This can be obtained in several fashions, either by running-on the threads towards the sides of the yarn body in the full width of the traverse of the guiding comb, but in greater density in 30 the comb,—or by opposing to the outer threads between the guiding comb and the running-on point a stationary or movable resistance so that the threads do not run-on in the full width of the traverse at the sides of the yarn body, but 35 with greater density.

An arrangement for denser winding-on at the two sides of the yarn body, represented and described in the patent application Serial No. 606,240, filed April 19, 1932, consists in reducing 40 the distance of the comb teeth towards the ends of the yarn body in the full width of the comb traverse, so that the threads come to lie closer and closer together toward the sides of the yarn body.

The same object can be obtained by leaving 45 the distance of the comb-teeth unchanged, and increasing instead the number of ends in each dent on either side of the yarn body in the approximate width of the comb traverse, so that by 50 way of example there are two ends in a dent over the cylindrical part of the yarn-body, three ends in the first dent of that part of the comb where the yarn body would otherwise begin to taper-off, four ends in the next dent, and so on.

This application is a division of my co-pending

application, Ser. No. 679,957, filed July 11, 1933.

The invention will be described in detail with reference to the accompanying drawings, wherein,

Fig. 1 is a somewhat diagrammatic side elevation, with parts in section, of a machine for winding a warp beam in accordance with my invention. 5

Fig. 2 is a plan view of the same machine,

Fig. 3 is a fragmentary front elevation of the 10 same machine,

Fig. 4 is a plan view of a modified form of machine for winding a warp beam with conically shaped ends in accordance with my invention, and 15

Fig. 5 is a detail front elevation of the comb adjusting mechanism of the machine shown in Fig. 4.

Referring first to Figs. 1-3, the threads to be wound are shown at 1 and the warp beam body 20 at 2. A guide comb 3 is mounted on a comb rod 4 provided with fingers 4a engaging a cam 5 for traversing the guide comb. The cam 5 is mounted upon a shaft 5a. The guide comb and the shaft 5a are supported in a cradle comprising 25 side arms 6, 7 which are susceptible of being balanced by counterpoise weights (not shown).

The cam shaft 5a carries a loose bush 33 fitted with a wire loop 32 having lateral stops 32a, 32b for the reduction of the traverse of the 30 threads adjacent the edges of the warp beam. The bush 33 with the wire loop 32 is traversed on the cam shaft 5a, by means of a separate lever arrangement 34, 35. The traversing movement is derived from the comb rod 4 and reduced 35 as against the traverse of the comb, by means of the relation of the lever 35 to the lever 34. The degree of shortening can be adjusted by shifting the pivot 36 in the slot of the lever 34. Moreover, the lever 34 may be of a different order 40 and may be pivotally connected at its end to lever 35, which in turn is pivoted to the bush 33. The wire loop 32 with its stops 32a and 32b therefore constantly has a shorter traverse than the comb 3. As a consequence, the outer threads 45 are prevented from making the full traverse of the comb and they are consequently crowded as shown particularly in Figs. 2 and 3, so that the yarn body receives a cylindrical shape up to the ends. 50

Figs. 4 and 5 show another embodiment of a warping frame for the production of cross-wound dyeing beams similar to the one shown in Figs. 1-3, but slightly changed in form to make them suitable for very smooth threads, such as silk, rayon, 55

double and twisted yarns and the like. In these kinds of yarns even the most pronounced crossing is at times unable to do away with the danger of cobwebbing of the outer threads at the ends of the yarn-body. In order to prevent this, the 5 yarn-body is made cone shaped at the outer ends similar to conical cross-wound cheeses. However, this shape cannot be obtained in the present case by means of the arrangement usual in cross winding frames for shortening the yarn traverse, because this is not possible in the case of the 10 yarn sheets or ribbons. According to the invention, the width of the yarn ribbon running-on is narrowed for each layer or group of layers, while 15 the traverse of the warping comb is not changed. In the illustrative machine shown in Figs. 4 and 5, a zig-zag comb 3a is used for the traverse of the yarn ribbon, this type of comb being known per se. The comb sections are in connection 20 with the guide screw 41 having right and left hand threads. A pair of bevel wheels 42, 43 acts upon one end of the guide screw 41. The shaft of the bevel wheel 43 carries a ratchet wheel 44 which is actuated by a pawl 45, the to and fro 25 movement of which is derived from the traversing movement of the comb rod with reference to the bracket 46. Every double traverse of the comb rod 4 therefore causes the ratchet wheel 44 to be turned by a certain amount, depending on

the pitch of the teeth and the number of teeth passed by the pawl on the return motion, so that the zig-zag comb can be correspondingly narrowed for the desired reduction of the width of the yarn sheet. 5

Fig. 4 shows that the cylindrical ends of the self-supporting yarn beam are obtained by feeding the threads more densely toward the sides of the yarn ribbon, as already explained above.

Having described my invention, 10

I claim:

1. A warp beam consisting of a plurality of threads cross-wound across the complete extent thereof, with the threads at the ends of the beam for the extent of the traverse thereof wound with 15 a greater transverse density than those at the remainder thereof, the wound body being self-supported, and having a true cylindrical lateral surface with no rounding of the ends.

2. A warp beam consisting of a plurality of 20 threads cross-wound across the complete extent thereof, with the threads at the ends of the beam for the extent of the traverse thereof wound with a greater transverse density than those at the remainder thereof, the wound body being self-supported and having a true cylindrical lateral surface with no rounding of the ends, 25 the end surfaces of the beam being conical.

GUSTAV KAHLISCH.
